By Cook & M^{Co} Carley J. M. J.

UNITED STATES PATENT OFFICE.

CHARLES E. CARTER, OF GILLESPIE, ILLINOIS.

OPERATING MECHANISM FOR MINE DOORS.

1,419,357.

Specification of Letters Patent. Patented June 13, 1922.

Application filed April 21, 1921. Serial No. 463,241.

To all whom it may concern:

Be it known that I, CHARLES E. CARTER, a citizen of the United States of America, a resident of Gillespie, in the county of Ma-
5 coupin, State of Illinois, have invented cer-
tain new and useful Improvements in Oper-
ating Mechanisms for Mine Doors, of
which the following is a full, clear, and ex-
act description, reference being had to the
10 accompanying drawings, forming a part of
this specification.

This invention relates to improvements in operating mechanisms for mine doors, and has for one of its objects the production of a
15 simple and inexpensive door operating de-
vice which is automatically actuated by a car
or tram as it moves along the track upon
which it is mounted.

Another object is to provide a mine door
20 which will open in a direction away from
the approaching car or tram regardless of
which direction said car or tram is travel-
ing.

Still another object is to provide a mine
25 door which, because it is capable of swing-
ing in either direction, will not be shattered
by the force of an explosion within the mine
but will be swung on its hinge thereby.

One of the most important branches of
30 coal mining is the management of the ven-
tilation, involving as it does the supply of
air to the men working in the pit, as well as
the removal of the inflammable gases that
may be given off by the coal. This is ef-
35 fected by carrying through the workings a
large volume of air which is kept continually
moving in the same direction, descending
from the surface by a pit known as an in-
take or downcast pit, and leaving the mine
40 by a return or upcast pit.

In laying out the mine it is customary to
drive the levels or roads in pairs, communi-
cation being made between them at intervals
by cutting through the intermediate pillar.
45 The air then passes along one road and re-
turns by the other. As the roads advance
other pillars are driven through in the same
manner, the passage first made being closed
by doors whereby the air is prevented from
50 taking a short cut back to the upcast, while
preserving free access between the different
districts without following the whole round
of the air-ways.

Most of the roads above referred to are
55 provided with tracks upon which trams op-
erate for the removal of broken coal, and

the purpose of the present invention is to
provide a means whereby the doors just
mentioned may be automatically operated
by said trams. 60

With the foregoing and other objects in
view, the invention comprises the novel con-
struction, combination and arrangement of
parts hereinafter more specifically described
and illustrated in the accompanying draw- 65
ings wherein is shown the preferred em-
bodiment of the invention. However, it is
to be understood that the invention compre-
hends changes, variations and modifications
which come within the scope of the claims 70
hereunto appended.

Fig. I is a horizontal section through a
level or road showing my improved door
operating mechanism in place therein.

Fig. II is a longitudinal section on line 75
II—II of Fig. I.

Fig. III is a transverse section through a
level or road showing my improved door op-
erating mechanism in place therein.

Fig. IV is a section on line IV—IV of 80
Fig. III.

Fig. V is a fragmentary section showing
means for returning the mechanism to its
normal position after its release.

In the drawings, A indicates a level or 85
road of a mine, which is provided with the
usual track B comprising rails C and ties D.

Supported in said level or road A is a door
frame 1, which is composed of timbers se-
cured in any suitable manner to the side 90
walls and ceiling of said level or road.

Hingedly supported within said door
frame 1 is a pair of doors 2, each of which is
secured to a vertical supporting shaft 3, said
shaft being mounted in suitable bearings 4, 95
one of which is fixed to the ceiling timber of
the door frame 1, and the other to a con-
crete base 5 imbedded in the floor of the
level or road A.

Located on the track B at points distant 100
from the doors 2 are bearings 6, said bear-
ings being secured in place by being fixed to
convenient ties D. Mounted in each of said
bearings is a short shaft 7 which supports at
its end adjacent the rail C an arm 8. Each 105
of the arms 8 extend upwardly above the
rails C and occupy a position in the path of
the wheels of a tram mounted thereon.

It will be noted by referring to Fig. I of
the drawing that each rail C of the track B 110
is provided with a pair of the arms 8, one of
said arms being located adjacent said rail

at a point distant from the doors 2. Bars 9 extending longitudinally of said rails have their opposite ends pivotally connected to said arms 8, whereby each pair of said arms 5 8 adjacent a rail C are operated simultaneously.

Secured to each of the short shafts 7 at its outer end is a downwardly extending arm 10, the purpose of which will be hereinafter 10 stated.

Rotatably mounted in suitable bearings, fixed to a tie D, and extending transversely of the track B is a shaft 11, which is provided at each of its ends with a bevel gear 12, said bevel gear 12 being adapted to mesh with a bevel gear 13 mounted on the shaft 3, whereby a rotary movement of the shaft 11 will impart a like movement to the shaft 3. 15

Fixed to the shaft 11 and extending downwardly therefrom is a pair of arms 14, one of which is located on said shaft 11 at a point adjacent each bevel gear 12. Links 15 pivotally connect the arms 14 to their associated arms 10, whereby a movement 20 of the bar 9 will be transmitted to the shaft 11 and from the shaft 11 through the bevel gears 12 and 13 to the doors 2.

In the operation of my improved door opening device the front wheels of a car or 30 tram which is mounted on the track B, and which is approaching a pair of doors 2, will contact with arms 8 and then travel over the bars 9. This is made possible because said bars 9 are arranged close to 35 the rails C and because the car wheels are sufficiently wide to contact with said bars 9. The arms 8, being capable of oscillation, will permit the bars 9 to move longitudinally and downwardly of the rails C 40 under the pressure of said car wheels until they have reached a point where their top faces are flush with the top of the ball of the rails.

Because the arms 10 are secured to the 45 short shafts 7 to which the arms 8 are secured and which short shafts 7 are rocked when the bar 9 is depressed, said arms 10 will likewise be oscillated, which oscillation will be transmitted through the link 15 and arm 14 to the shaft 11, and through the bevel gears 12 and 13 to the door supporting shafts 3. It is apparent from the drawing 50 that the doors will remain in their open positions as long as the car wheels retain the bars 9 in their depressed positions.

To return the door operating mechanism to its normal position after the car wheels have moved from the bars 9, I provide a weight 16 which is mounted on the shaft 60 11 and hangs in a vertical line therefrom. As said shaft 11 is rocked in either direction, said weight will be carried upwardly in an arc of a circle, and when the pressure is removed from the bars 9, said weight 65 will by gravity swing back to its position

of rest and thereby return the operating mechanism to its normal position.

Depressions 9' are formed in the bars 9 to allow clearance for the doors 2 to swing when operated. 70

To prevent the passage of air through the space between the bottom of the doors and the surface of the road, I provide each of said doors with a section of canvas or similar material 17, which is attached to said doors and depends therefrom whereby said opening is closed and the air prevented from passing therethrough. 75

Although the doors are operated automatically, it will be observed that they can 80 also be pushed open by a person walking through the doorway, and when released they will return to their closed positions.

I claim:

1. An automatically operated mine door 85 comprising a door secured to a vertically supported shaft and adapted to extend across a track, and car operated means co-operating with said door comprising pivoted arms, the upper ends of which are adapted 90 to extend above said track and into the path of a car on the track, a bar extending longitudinally of said track and pivotally connected to said upper ends of the pivoted arms at its ends, a rockable shaft, an arm 95 secured to said rockable shaft, links connecting said arm on the rockable shaft to said pivoted arms, a bevel gear mounted on said rockable shaft, a second bevel gear mounted on the vertical door supporting 100 shaft adapted to mesh with said first mentioned bevel gear, whereby the engagement of one of said pivoted arms by a car moving in either direction will actuate said car operated means to open the door in a direction away from said car and retain it in such position while such engagement continues, and means whereby said car operated means is returned to its normal position 105 when said car and said car operated means 110 are disengaged.

2. Automatically operated mine doors comprising a pair of doors, each of which is secured to a vertically supported shaft and is adapted to extend transversely of a track, and car operated means associated with said doors comprising pivoted arms located at points remote from said doors, the upper ends of which are adapted to extend above said track and into the path 115 of a car on the track, bars extending longitudinally of said track, one of which is arranged adjacent each rail thereof, said bars being pivotally attached at their ends to said upper ends of the pivoted arms, a 120 rockable shaft, arms secured to said rockable shaft, links connecting each of said arms on the rockable shaft to its associated pivoted arm, bevel gears mounted on said rockable shaft at the ends thereof, bevel 125 gears 130

gears mounted on the vertical door supporting shafts, each of which mesh with one of the first mentioned bevel gears, whereby the engagement of one of said 5 pivoted arms by a car moving in either direction will actuate said car operated means to open the doors in a direction away from said car and retain it in such position while such engagement continues, and means whereby said car operated means is 10 returned to normal position when said car and said car operated means are disengaged.

In testimony that I claim the foregoing I hereunto affix my signature.

CHARLES E. CARTER.
